UNITED STATES PATENT OFFICE.

HAAKON A. MARTIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

TOTAL-PRINTING CASH-REGISTER.

1,013,193.

Specification of Letters Patent.

Patented Jan. 2, 1912.

Application filed April 9, 1910. Serial No. 554,399.

To all whom it may concern:

Be it known that I, HAAKON A. MARTIN, a subject of the King of Norway, residing at Dayton, in the county of Montgomery and State of Ohio, have invented certain new and useful Improvements in Total-Printing Cash-Registers, of which I declare the following to be a full, clear, and exact description.

- 10 This invention relates to accounting machines and more particularly to the printing mechanism thereof, and its principal object is to provide mechanism for printing the total as well as the items upon a record strip.
- 15 Another object of this invention is to provide a plurality of impression means for taking impressions from item and total type carriers, the total impression means being normally inoperative but constructed to be
- 20 placed in operative condition upon the operation of a total manipulative device.

Another object of the invention is to provide a couple for feeding the record strip, one member of which is operated to feed the strip when an item is recorded and the other member operated to feed the strip when the total is recorded.

Another object of this invention is to provide counters for registering the number of 30 different classes of transactions that may be entered in the machine.

Another object of this invention is to provide novel combined transferring and resetting devices for the registering wheels of 35 the counters.

With these and incidental objects in view, the invention consists in certain novel features of construction and combinations of parts, the essential elements of which are 40 set forth in appended claims, and a preferred form of embodiment of which is hereinafter described with reference to the drawings which accompany and form part of the specification.

- 45 Figure 1 is a central transverse sectional view through a machine of the type shown in the patent to Cleal and Reinhard 580,378 issued April 13th, 1897, with the improvements applied thereto. Fig. 2 is an end elevation of the machine showing the printing mechanism. Fig. 3 is an enlarged side elevation of the item and total recording devices and the inking mechanism for same. Fig. 4 is a partial front elevation of the 55 total type carriers, showing their connec-

tion with the registering mechanism. Fig. 5 is a partial side elevation of one of the key banks of the machine showing the total lever and connections for releasing the operating mechanism by the operation of said total lever. Fig. 6 is an end elevation of the operating gearing and lock for the operating mechanism. Fig. 7 is a sectional view taken alongside of the special counters for recording the different classes of transactions entered in the machine. Fig. 8 is a view similar to Fig. 7 but looking in the opposite direction. Figs. 9, 10 and 11 are different views of the counter construction showing the actuating, transferring and resetting devices for same.

Described in general terms the machine comprises several banks of manipulative devices which control the differential movement of actuating segments or devices, the latter in turn operating the indicating and registering mechanisms. These actuating segments set up item type carriers from which an impression is taken by the further operation of the machine. The registering mechanism is constructed to accumulate the items indicated and recorded, and connected with this registering mechanism or totalizer is a series of total type-carriers from which may be taken an impression whenever desired. The machine is also provided with a series of counters for recording the number of different classes of transactions entered in the machine and these counters are provided with novel combined transferring and resetting devices.

The improvements have been shown applied to a machine employing the English monetary system for indicating, totalizing and recording transactions, but it is to be understood that this type of machine has been used simply for the sake of illustration and that any other monetary system may be employed.

Manipulative devices such as keys 1 are arranged in groups or banks and when depressed against the tension of their springs 2 are latched by a detent 3. The operation of any of these keys 1 elevates its detent 3 and this detent is provided with a stud 4 which engages with the forward end of an arm 5 secured to a shaft 6 so as to rock said shaft. This shaft 6 extends horizontally through the machine and is provided at its right hand end with a rearwardly extending 110

arm 7, see Fig. 6, which has at its extreme rearward end an upward extension 8 which enters into a recess 9 formed on the outer edge of a disk 10 secured to a gear 11. From this description it will be seen that the gear 11 and an operating handle 12 connected thereto will be locked until one of the keys 1 is depressed. The operating handle 12 is provided with a pinion 13 which meshes with a large gear 14 which in turn meshes with the gear 11. The gear 11 is secured to one end of a transverse shaft 15 and this gear 11 meshes with a similar gear 16 which is secured to the right hand end of a shaft 17 extending horizontally through the machine. Upon the release of the operating handle 12 by the operation of any one of the keys, said handle may be rotated and it will be seen that the shafts 15 and 17 will also be rotated. This shaft 17 has an arm 18 secured thereto, see Fig. 1, and to the free end of this arm is secured one end of a link 19, the other end of said link being attached to the free end of an arm 20 secured to a shaft 21. Upon the rotation of the shaft 17 by the crank handle 12 the shaft 21 will be rocked, and secured to this shaft 21 are segments 22, one for each bank of keys. These segments, upon the first movement of the shaft 21, will be rocked forwardly and downwardly, and shoulders 23 formed on said segments will be engaged by latches 24 pivoted to actuators 25 of the banks in which keys are depressed. Upon the return movement of the segments 22 the actuators 25 carrying the latches 24 of the banks in which keys are depressed will also be carried rearwardly distances determined by the value of the keys depressed. These actuators 25 are loosely mounted upon the transverse shaft 21 and are disconnected from the segments 22 by pawls 26 of the latches 24 engaging with the inner ends of the depressed keys. This construction is well known in the art and is fully shown and described in the before mentioned patent of Cleal and Reinhard.

The actuators 25 are provided with teeth 27 upon their outer edge which mesh with gears 28, these gears in turn meshing with smaller gears 29 secured to indicators 30 which are mounted loosely upon a transverse rod 31. The gears 28 also mesh with gears 32 loosely mounted upon a transverse rod 33 and these gears have secured to their sides, see Fig. 4, smaller gears 34. Adjacent to the gears 34 are similar gears 35 which are connected by sleeves 36 to registering wheels 37 of the totalizer. The gears 34 and 35 are normally disconnected and just previous to the rearward movement of the actuators 25 they are connected by a pinion 38 for each pair of gears 34 and 35 so that the rearward movement of the actuators will be conveyed to the wheels 37 of the totalizer through

gears 28, 32, 34, 35, and pinions 38. These pinions 38 are mounted in the upper ends of arms 39 secured to a shaft 40. This shaft 40 has a downwardly extending arm 41, the lower end of which is connected to the forward end of a link 42, the rearward end of the latter being forked so as to straddle the shaft 17. A pin 43 extending from the link 42 projects into a cam groove 44 in a disk 45 secured to the shaft 17 adjacent to the link 42. The shape of the groove 44 in the disk 45 is such that just before the actuators 25 move rearwardly the link 42 will be moved forwardly to carry the pinions 38 into engagement with each pair of gears 34 and 35 to connect them for movement together. The actuators are returned to their normal position at the beginning of each operation of the machine by extensions 46 of the segments 22 which engage with the actuators 25 and thereby carry them to their normal positions. During this movement the pinions 38 are out of mesh with the gears 34 and 35.

The gears 28 are fast to the inner ends of nested sleeves 47 which surround the shaft 15 and the other ends of said sleeves carry printing segments 48 for recording items upon a record strip 49, see Figs. 2 and 3. This strip is fed from a supply roll 50 over a platen 51, thence over a second platen 52, the latter for recording the total, as hereafter described, and thence to a storage roll 53. The platen 51 which is for taking impressions from the item type carriers 48 is mounted in a movable frame 54, the latter having extending therefrom a pin 55 which projects into a cam groove 56 of a disk 57 secured to the left hand end of the shaft 15. The shape of the cam groove 56 is such that upon the rotation of the shaft 15 by the operating handle 12, the frame 54 carrying the platen 51 will be first lowered to feed the record strip and ink the type-carriers 48, as hereafter described, and then be raised to take an impression upon a check strip after which it is lowered to permit the ejection of the check and is finally raised to take an impression upon the record strip 49. The previously mentioned check strip 58 is fed from a suitable supply roll, not shown, between feed and impression rollers 59 and 60, shown in dotted lines in Fig. 2 and thence over the impression roller or platen 51. As previously described, the first elevation of the frame 54 carrying the platen 51 will take an impression upon the check strip 58 from the item type carriers 48 and by this movement of the frame 54 a portion of the check strip will be severed so that a check ejector 61 may grip the check and eject it as the platen frame 54 is lowered. A guide plate 54^a suitably secured to the frame 54 guides the severed check between the total platen 52 and the total type carriers hereinafter described, and into a

- suitable check receptacle (not shown) from which it may be removed and handed to the customer as a receipt. Previous to the printing and ejecting of the check an ink pad 62 will be moved into position to ink the adjusted types and then move out of the path of the platen 51. This ink pad 62, see Fig. 3, is carried in the lower end of an arm 64 which is pivotally supported at its upper end in the outer end of an arm 63, loosely mounted upon the outermost one of the nested sleeves 47. This arm 63 is provided with a collar to which is fastened a sleeve 640. This sleeve has an ear 165 projecting rearwardly therefrom and to which is connected the upper end of a link 66, the lower end of said link being forked to straddle the shaft 17. Extending from this link 66 is a pin 67 which projects into a cam groove 68 formed in a disk 69 secured to said shaft 17 and the shape of this groove is such so as to rock the ink pad to ink the type, previous to the elevation of the platen frame 54 by its cam disk 57.
- 25 The operation of the machine so far described is the same as that shown and described in the above mentioned Cleal and Reinhard patent and now will be described the improvements applied to this type of machine, but it is to be understood that these improvements are not to be limited to the particular style of machine to which for illustration they have been shown as applied.
- 35 Meshing with each one of the gears 35, see Figs. 1 and 4, is a similar gear 70 which is fast to the inner end of one of a series of nested sleeves 71, with the exception of the gear 70 in mesh with the gear 35 of the farthings or lowest value wheel which is rigidly secured to a shaft 72 upon which the sleeves 71 are loosely mounted. The three left hand registering wheels 37 shown in Fig. 4, are not actuated directly by the actuators 25 as is the case with the four right hand registering wheels, but are arranged to receive their movement by suitable transfer devices not shown, but which are well known in the art. These wheels have gears 35 connected thereto and these gears in turn mesh with gears similar to the gears 70 which in turn are connected to the ends of their respective sleeves 71. At their other ends the sleeves 71 and the shaft 72 have secured thereto total printing wheels 73, the end of the shaft 72 being extended and supported by a bracket 74 secured to the printer frame 75.
- 60 The total type carriers 73 are inked by a roller 76 carried in the lower end of a frame 77 which is pivoted at its upper end as at 78 to a frame 79 loosely pivoted upon the end of the shaft 72. A spring 80 coiled about the pivotal point 78 holds the roller in contact with the type of the total type carriers
73. Projecting from the frame 79 is a stud 81 which enters into a recess 82 formed in a slide 83. This slide is provided with elongated slots 84 and 85 through which pass the shaft 72 and a stud 86 respectively, the latter projecting from the bracket 74. The slide is also provided with a cam slot 87 into which projects an anti-friction roller 88 extending from the arm carrying the previously described ink pad arm 64. By reference to Fig. 3 it will be seen that as the arm 64 carrying the roller 88 is rocked downwardly it will cam the slide 83 forwardly and by the stud 81 riding in the recess 82 of said slide rock the frame 79 and thereby 75 the frame 77 carrying the roller 76 to ink the total type carriers. This roller 76 will be withdrawn from the type of the total type carriers that are in printing position upon the return of the arm 63 carrying the ink pad 62 for the item type carriers.
- 20 The total platen 52 previously described is mounted in a bracket 90 secured to the frame 54 carrying the item printing platen 51. Normally the total platen 52 is in such 90 position that when the frame 54 and bracket 90 are elevated the said platen will not contact with the total type carriers 73 but whenever a total is desired to be recorded this platen 52 is slightly elevated relative 95 to the bracket 90 by means hereafter described so that when the frame 54 is elevated by the cam disk 57 the said platen will contact and take an impression from the total type carriers 73.
- 30 A total lever or manipulative device 91 is pivoted upon the side frame of the machine and has projecting therefrom a flange 92 which normally rests against the outer edge of a lever 93 which is pivoted as at 105 94 to the side frame of the machine and held in the position shown in Fig. 2 by a coiled spring 95, the ends of which are fastened to an extension 96 of the lever 93 and to a plate 124 hereafter described. This 110 lever 93 is provided with a pin 98 at its upper end which rests against the forward edge of a downwardly extending arm 99 fast upon a rod 100 mounted in the bracket 90. Secured to this rod 100 and extending upwardly therefrom are cam plates 101, only one of which is shown. In depressions 102 of these cam plates normally rests the supporting rod 103 of the platen roller 52. From this it will be seen that when the total 120 lever 91 is pulled downwardly the lever 93 will be rocked rearwardly about its pivotal point 94 and by pin 98 rock the arm 99 rearwardly and the cam plates 101 forwardly thereby camming the platen roller 52 upwardly in recesses 104 of the bracket 90 so that when the said bracket is elevated with the frame 54 the roller 52 will contact with the type carriers 73 to record the total. The arm 99 is provided with a pin 105, which, 130

when the said arm is rocked rearwardly upon depressing the total lever 91, will be moved in the rear of a flange 106 of a plate 107 secured to the forward end of a bell crank lever 108, see Fig. 5, the latter being pivoted upon the side frame of the machine. Upon the operation of the crank handle 12, the shaft 17, as previously described, will be rotated and a cam 109 secured thereto will engage with a roller 110 projecting from the upwardly and rearwardly extending portion of the bell crank 108 and rock said bell crank in a clockwise direction thereby carrying the flange 106 in front of the pin 105 so as to prevent the return of the arm 99 and the cam plates 101. The first upward movement of the platen frame 54 under this condition will bring the roller 52 into contact with the total 20 type-carriers 73 to record the total upon the record strip 49. During this upward movement of the platen frame the lever 93 will be released as hereafter described and the pin 105 on the arm 99 will pass above the flange 106 of the plate 107 and be returned 25 toward its normal position by a spring 111, the ends of which are fast to a pin 112 projecting from one of the cam plates 101 and to the side of the bracket 90. The arm 99 and the cam plates 101 will be prevented 30 from being fully returned to their normal position by the pin 105 on the arm 99 contacting with a second flange 206 of the plate 107. In this position the cam plates 101 still hold the platen roller 52 in position to 35 take an impression from the type-carriers 73. This flange 206 is slightly in advance of the flange 106 so that when the platen frame 54 and the bracket 90 are lowered the pin 105 will pass from behind the flange 206 and in front of the flange 106, thus freeing the arm 99 so that the spring 111 may 40 return said arm and the cam plates 101 to their normal position. From this it will be seen that as the platen frame 54 and the bracket 90 are raised the second time, as 45 previously described, the platen roller 52 will not contact with the total type carriers 73, the supporting rod 103 of said platen roller 52 being then in the depressions 102 of the cam plates 101.

It will be recalled that the operating handle 12 is normally locked, so that to take a total some means must be provided to 55 release said handle. To this end the left hand bank of keys as shown in Fig. 5 is what is known in the art as a divided bank, that is, one in which a key of each division may be depressed during a single operation 60 of the machine. The five upper keys 1 of this bank represent amounts and the four lower keys 113 different classes of transactions such as "no sale," "received on account," "charge," and "paid out." The five 65 upper keys 1 of this bank actuate a detent

plate 3 in the same manner as previously described, while key pins 114 of the four lower keys are arranged to be engaged by a detent plate 115 and latched in their depressed positions. These key pins 114 also engage with inclined slots 116 in a segmental plate 117 and elevate said plate. The detent 70 115 and plate 117 are suitably mounted upon the side frame of the machine and the plate is provided with a rearwardly extending 75 arm 118, which, when the said plate 117 is elevated by the depression of any of the lower four keys, will contact with the arm 5 projecting forwardly from the rod 6 and coöperating with this bank of keys, and 80 rock said rod to release the crank handle.

Projecting from the lever 93 is a pin 119 which when said lever is rocked by the operation of the total lever 91 will engage with inclined slots of the detent 115 and plate 117 85 and elevate said detent and plate in the same manner as the key pins 114. When the lever 91 is fully depressed the detent plate will be returned to its normal position by a spring 120 and latch lever 93 in its rocked or adjusted position. The elevation of the plate 117 by the pin 119 will, through the arm 118 engaging with the arm 5, rock the rod 6 so as to release the machine in the same manner as if one of the special transaction keys were 90 operated.

The detent 115 is provided with a downwardly extending arm 121 which has projecting therefrom anti-friction roller 122. This roller normally rests in the forward 100 end of an inclined cut away portion 123 of a plate 124 slidably mounted upon the frame work of the machine. At its rear end this plate is provided with an anti-friction roller 125 with which a cam plate 126 secured to 105 the rock shaft 21 engages, upon the oscillation of said shaft, to move said plate 124 forwardly and by the incline 123 elevate the detent 115 to release the depressed key 113 or the lever 93 operated by the total lever 91. 110 This divided bank construction is well known in the art and is fully shown and described in Patent No. 897,575 issued to F. H. Bickford, September 1st, 1908, and for a further description thereof, reference may 115 be made to said patent.

The next feature of the invention to be described is the feeding mechanism for the record strip. This mechanism is constructed so that a greater extent of the strip is fed 120 when the total is recorded than when the items are recorded in order to print the total at the bottom of the listed items.

The supply roll 50 and the storage roll 53 for the record strip are suitably mounted 125 upon the platen frame 54 and adjacent to the storage roll 53 is a ratchet disk 127 loosely mounted upon a stub shaft 128 which also carries the storage roll 53. Attached to the side of the ratchet disk 127 is a pawl 129 130

which is held into engagement with the teeth of a pinion 130, also loosely mounted upon the stub shaft 128, by a spring 131. Meshing with this pinion 130 is a rack bar 132 secured to the side of a frame 133, which is provided with an elongated slot 134 through which the stub shaft 128 extends. This frame 133 near its forward edge is also provided with an elongated slot 135 which 10 near its upper edge has a rearwardly extending recess 136 in which projects a pin 137 extending from an arm 138 suitably secured to the side frame of the machine. By reference to Fig. 2 it will be seen that as the 15 frame 54 is lowered by its cam disk 57 the pinion 130 will be rotated as it travels over the teeth of rack 132 and as said pinion is rotated it will also rotate the ratchet disk 137 and the storage roll 53 by the pawl 129. 20 A pawl 139 engages with the teeth of the ratchet disk 127 to prevent any retrograde movement of said disk and the storage roll 53. It will be seen by reference to Figs. 2 and 3 that the item type carriers 48 are in 25 the rear of the total type carriers 73 and in order properly to feed the record strip 49 in the taking of a total so that said total will appear at the bottom of the recorded items additional devices other than those just described must be provided to feed the strip 30 the proper distance. Such devices will now be described.

By the operation of the total lever 91 the lever 93 will be rocked, and extending rearwardly from said lever is an arm 140 which is provided with a roller 141 that extends in the upper end of the slot 135 in the frame 133 and this roller 141 will carry the said frame 133 rearwardly with the stub shaft 40 128 of the storage roll 53 acting as a pivot for said frame. This frame is provided with a recess 142 which passes around a roller 143 projecting from a lever 144 when the frame 133 is rocked rearwardly upon the 45 depressing of the total lever 91. The lever 144 carrying the roller 143 is pivoted to the side frame of the machine as at 145 and is provided with a cam slot 146 into which projects a roller 147 extending from the cam 50 plate 126 which is secured to the rock shaft 21. It will be recalled that this rock shaft 21 is rocked in the direction of the arrow, see Fig. 2 during the first part of an operation of the machine and as the roller 147 55 rides in the cam slot 146 the forward end of the lever 144 will be elevated carrying with it the frame 133 which, as previously described, has been connected thereto. As this frame 133 is elevated by the rocking of the 60 lever 144, the rack bar 132 will rotate the pinion 130 and by pawl 131 rotate the ratchet disk 127 and the storage roll 53, so as to feed the strip 49 far enough to bring the last recorded item in advance of where 65 the total is to be printed upon the record

strip. The return movement of the lever 144 will carry the frame 133 and rack 132 to its normal position during which movement the pinion 130 will idly rotate about the stub shaft 128, the storage roll 53 carrying 70 the record strip being held in its advanced position by the retaining pawl 139. When the detent 115 is released as previously described, the arm 93 will be returned to its normal position by the spring 95 and 75 through the roller 141 projecting from the arm 140 of the lever 93, the said frame 133 carrying the rack 132 will also be returned to its normal position as shown in Fig. 2.

From the above description it will be seen 80 that the pinion 130 and the rack bar 132 comprise a couple, one member of which, pinion 130, is moved to feed the record strip a certain extent, the other member, rack bar 132, being moved to feed the strip a greater extent than that fed by the movement of the first mentioned member. It is to be understood that this form of feeding mechanism is not to be limited to total printing machines but may be employed on any machine 85 using a record strip which it is desired to feed variable extents.

During the operation of the machine to record items the pin 143 will pass directly in 90 the rear of a portion of the frame 133 which is cut upon an arc of a circle struck from the pivotal point of the frame 144 so that the frame 133 cannot be rocked rearwardly and consequently the total lever 91 will be locked from operation.

It will readily be understood that the feeding mechanism just described, may be employed to advantage in constructions wherein a single set of type carriers is employed to record both items and totals, and 105 certain of the claims are intended to cover such constructions and are not to be limited to the form shown and described.

The next feature of the invention to be 110 described is the counters for registering the number of the different classes of transactions and also the total number of all transactions.

Referring now to Figs. 7 and 8 the special 115 counters 148, 149, 150, 151 and 152 represent respectively "paid out", "charge", "received on account", "no sale", and the "total" or "customer counter". These counters are mounted in a frame 153 which is suitably secured to one of the frames of 120 the machine between two of the banks of keys and adjacent to one side of the counter frame 153 is a plate 154 provided with elongated slots 155 through which extend pins 156 secured to the frame of the machine. At 125 its forward edge this plate 154 is provided with inclined slots 157 arranged at different angles and with which coöperate the key pins 114 of the special transaction keys 113. From the angles of the slots as shown in 130

Fig. 7 it will be seen that the said plate 154 is arranged to be moved differentially in opposite directions. Upon a pin 158 projecting from one side of the frame 153 are two 5 centrally pivoted arms 159 the rearwardly extending portions of which are arranged to contact upon the opposite sides of a pin 160 projecting from the plate 154. The forwardly extending portion of each arm 159 is 10 upon the opposite side of the pivotal point 158 from that of the rearwardly extending portion of the arms and they are connected at their extreme forward ends by a spring 161, a pin 162 projecting from one of the 15 sides of the frames 153 limiting the movement of the arms 159 by the spring 161. From this it will be seen that after the key pins 114 adjust the plate 154 and the keys are released the said plate will be returned 20 to its normal central position by the spring 161 and the arms 159. The differential movement of the plate 154 is imparted to an actuating plate or device 163, see Fig. 8, by a link 164 the upper end of which is connected to the plate 154 at the point where the pin 160 projects therefrom, the lower end of said link 164 being fastened to the rear end of an arm 165, the forward end of which is secured to one end of a short rod 166 30 which is mounted in the sides of the frame 153. At its other end the rod 166 has secured thereto an arm 167 similar to the arm 165. The rear end of the arm 167, see Fig. 8, is secured to the lower end of a link 168, the 35 upper end of which is provided with a pin 169 that projects through an elongated slot 170 of the actuating device 163. This pin 169 also projects through a circular slot 171 formed in one of the sides of the frame 153, 40 this latter slot acting as a guide for the pin 169. From this it will be seen that any movement of the plate 154 by the key pins 114 will be imparted to the actuating device 163. This actuating device 163 is provided 45 with extensions 172 for operating the various special counters. All of these extensions, as will be seen from Fig. 8, are normally out of position to engage with rollers 173 carried by the operating plates 174 of the various 50 special counters with the exception of the projection 172 which cooperates with the roller 173 of the total or customer counter 152, this projection, no matter to what position the actuating device 163 is moved, being 55 always in position to engage with its roller 173 when said actuating device 163 is moved forwardly. The angles of the slots 157 formed in the plate 154 are such that upon the operation of any special key 113 its 60 pin 114 will move said plate and the actuating device so as to bring one of the projections 172 into cooperation with the roller 173 of the corresponding counter. The bottom four projections are so located upon the 65 actuating device 163 that when any projec-

tion 172 is brought into coöperation with its respective counter none of the other projections will be in coöperation with their counters. After the actuating device 163 has been adjusted to bring one of the projections 70 172 into coöperation with its roller 173 the said actuating device 163 will be moved forwardly at the beginning of the operation of the machine by a roller 175 which projects into a cam slot 176 formed in the rearward 75 end of the actuating device or slide 163. This roller 175 is carried by the upper end of an arm 177 which is secured to the rock shaft 21. After the slide is returned to its normal position and the special keys 113 are 80 released the readjusting device comprising the arms 159 and the spring 161 will return the said slide 163 and the plate 154 to their normal positions.

Each of the counters 148 to 152, inclusive, 85 has an operating plate 174 which is pivoted upon the counter supporting shaft 178, see Fig. 9. Each of these plates 174 is provided with a spring pressed pawl 179 which as said plate is rocked forwardly, as previously described, will engage with the teeth of a ratchet wheel 180 secured to the units counter wheel and rotate said wheel one unit. The units wheel is provided on the side opposite to that of the ratchet wheel 90 180 with a star wheel 181, see Fig. 10, to which is pivoted a combined transferring and resetting pawl 182. Secured to the counter shaft 178 and in the same plane as the pawl 182 is a combined transfer and resetting disk 183. This pawl 182 projects beneath the flange of the tens counter wheel and said flange is provided with projections 184 which extend inwardly toward the shaft 178, as shown in Fig. 11. In the figure just mentioned the units counter wheel 185 carrying the pawl 182 shown in said figure, stands at "eight" and at the next movement of said wheel the forward end of the pawl will engage with the camming projections 186 of the disk 183 and elevate the free end of said pawl so that a shoulder 187 thereof will be brought into engagement with one of the projections 184 of the tens wheel and upon the next increment of movement of the units wheels will carry the tens wheel one step or until the head of the pawl is drawn off of the projection 186 by its spring 188. As the transfer between the tens and the hundredth wheel is identical 110 120 with that just described it is thought that no further description is necessary.

Each of the rollers 173 on the plates 174 project through openings 189 in one of the sides of the frame 153 and the movements 125 of said plates are limited by the contact of the rollers with the ends of the slots or openings 189, each of the plates being returned to its normal position after being operated by its actuating device 163 by a 130

spring 190 which is secured to the lower end of the plate 174 and to the frame 153.

Each of the counter shafts 178 has secured to one end thereof a knurled wheel 191 by which the said shafts may be rotated. Each of these shafts is flattened upon one side so that when the shaft is rotated by its wheel 191 it will carry the disk 183 therewith. During the rotation of the disks 183 10 the projections 186 will engage with the head of the pawls 182 and carry the same and the wheels to which they are connected until "zero" appears. Each of the knurled wheels 191, see Fig. 7, is provided with a 15 V shaped notch 192 with which prongs 193 projecting from a segmental plate 194 engage so as to prevent any movement of said wheels. The segmental plate 194 carrying the prongs 193 is held in this position by a 20 coiled spring 195 and is elevated to release the wheels 191 by lifting the projection 196 which extends toward the front of the machine. When any of the wheels 191 is started the plate 194 will be held in its elevated 25 position by one of the prongs bearing upon the periphery of the corresponding wheel 191 but as soon as the V shaped notch 192 presents itself the plate carrying the prong will be lowered by its spring 195 to bring 30 the prong into position positively to arrest the wheel 191 at the end of the rotation thereof at which time the counter wheels 185 are returned to zero position.

A suitable hinged cover 197 partially 35 shown in Fig. 7, is provided for the special counters and this cover has a lug 198 which normally rests above the forward end of the projection 196 of the slide 194. When the slide 194 is elevated to enable the resetting 40 of any or all of the special counters the forward edge of the projection 196 passes in the path of the lug 198 and prevents the complete closing of the cover 197 until the counters are reset and the slide returned to 45 normal position.

While the form of mechanism herein shown and described is admirably adapted to fulfil the objects primarily stated it is to be understood that it is not intended to confine the invention to the one form of embodiment herein shown and described as it is susceptible of embodiment in various forms all coming within the scope of the claims which follow.

55 What is claimed is:

1. In a feeding mechanism, the combination with a couple for feeding a record strip, of means for moving one member of said couple to feed the strip a certain extent and 60 for moving the other member of the couple to feed the strip a greater extent than that fed by the movement of the first member.

2. In a feeding mechanism, the combination with a couple comprising a pinion and 65 a rack bar for feeding a record strip, of

means for moving the pinion over the rack bar to feed the record strip a certain extent and for moving the rack bar to rotate the pinion to feed the strip a greater extent than that fed by the movement of the pinion over 70 the rack bar.

3. In a machine of the class described, the combination with means for recording upon a record strip items and the total thereof, of a couple for feeding the record strip, and 75 means for moving one member of the couple to feed the strip when items are recorded and moving the other member of said couple to feed the strip when the total is recorded.

4. In a machine of the class described, the combination with means for recording upon a record strip items and the total thereof, of a couple comprising a pinion and a rack bar for feeding the record strip, and means 85 for moving the pinion over the rack bar to feed the strip when items are recorded and moving the rack bar over the pinion to feed the strip when the total is recorded.

5. In a machine of the class described, the 90 combination with means for recording upon a record strip items and the total thereof, of a frame carrying the record strip, a pinion mounted on the frame, a rack bar meshing with the pinion, and means for moving 95 the frame and thereby rotating the pinion as it travels over the rack to feed the strip when items are recorded and moving the rack to rotate the pinion to feed the strip when the total is recorded.

6. In a machine of the class described, the combination with type carriers for recording upon a record strip items and the total thereof, of a frame carrying the record strip, means for moving the frame to take impressions from the type carriers, a couple for feeding the record strip one member of which is carried by the frame to feed the record strip when items are recorded, and means for moving the other member to feed 100 the record strip when the total is recorded.

7. In a machine of the class described, the combination with means for recording upon a record strip items and the total thereof, of a couple for feeding the record strip, means for moving one member of the couple to feed the strip when items are recorded and moving the other member of said couple to feed the strip when the total is recorded, and mechanism preventing movement of the latter member to feed the strip when items are recorded.

8. In a machine of the class described, the combination with means for recording upon a record strip items and the total thereof, of a couple for feeding the record strip, operating mechanism for moving one member of the couple to feed the strip when items are recorded and moving the other member of said couple to feed the strip when the 125

total is recorded, the latter member being normally disconnected from the operating mechanism, and a manipulative device for connecting said member to the operating mechanism.

9. In a machine of the class described, the combination with means for recording upon a record strip items and the total thereof, of a couple comprising a pinion and a rack bar 10 for feeding the record strip, means for moving the pinion over the rack bar to feed the strip when items are recorded, means for moving the rack bar to rotate the pinion to feed the strip when the total is recorded, the 15 said rack bar being normally disconnected from its moving means, and a manipulative device for connecting the rack bar and its moving means.

10. In a machine of the class described, 20 the combination with a set of type carriers for recording upon a record strip an itemized statement, of a totalizer accumulating the items as they are recorded, a second set of type carriers connected to the totalizer 25 for recording the total upon the record strip, a couple for feeding the record strip, and means for moving one member of the couple to feed the strip when items are recorded and moving the other member of said couple 30 to feed the strip when the total is recorded.

11. In a machine of the class described, the combination with a set of type carriers for recording items upon a record strip, of a second set of type carriers for recording 35 upon the strip the total of said items, a couple for feeding said strip, means for moving one member of the couple to feed the strip when the items are recorded and moving the other member of the couple to feed 40 the strip when the total is recorded, the latter member being normally inoperative, a pair of platens one for each set of type carriers, the platens coöperating with the total type carriers being normally inoperative, 45 and a manipulative device for rendering the total platen and the inoperative member of the feeding couple operative.

12. In a machine of the class described, the combination with a set of type carriers 50 for recording items upon a record strip, of a second set of type carriers for recording upon the strip the total of said items, a couple comprising a pinion and a rack bar for feeding said strip, mechanism for moving the pinion over the rack bar to feed the strip when the items are recorded, means 55 for moving the rack bar to rotate the pinion when the total is recorded, the said rack bar being normally disconnected from its moving 60 means, a pair of platens one for each set of type carriers, the platen coöperating with the total type carrier being normally inoperative, and a manipulative device for connecting the rack bar with its moving

means and rendering the total platen operative.

13. In a machine of the class described, the combination with a set of type carriers for recording items upon a record strip, of a second set of type carriers for recording 70 upon the strip the total of said items, a movable frame carrying platens coöperating with the different sets of type carriers, the total platen being normally out of printing position, means for moving said frame, and 75 a manipulative device for bodily moving said total platen to bring it in printing position so that when the frame is moved the total will be recorded upon a record strip.

14. In a machine of the class described, 80 the combination with a set of type carriers for recording items upon a record strip, of a second set of type carriers for recording upon the strip the total of said items, a movable frame carrying platens coöperating 85 with the different sets of type carriers, the total platen being normally depressed so that when the frame is moved the said platen will not take an impression from the total type carriers, means for moving the 90 frame, and a manipulative device for bodily elevating the total platen.

15. In a machine of the class described, the combination with a plurality of type carriers for recording upon a record strip items 95 and the total thereof, operating mechanism for said type carriers, means normally locking said operating mechanism, manipulative devices controlling the movement of the type carriers to record the items and the unlocking of the operating mechanism, and an additional manipulative device controlling the recording of the total and the unlocking of said mechanism.

16. In a machine of the class described, 105 the combination with a set of type carriers for recording items upon a record strip, of a second set of type carriers for recording upon the record strip the total of said items, a movable frame, platens carried thereby 110 and coöperating with the different sets of type carriers, the total platen being normally out of printing position, operating mechanism for moving the frame and the type carriers, manipulative devices controlling the 115 extent of movement imparted to the item and total type carriers by the operating mechanism, means normally locking said mechanism operated by the manipulative devices, an additional manipulative device for positioning the total platen and unlocking the operating mechanism so that when the latter is operated the total will be recorded upon the record strip, a couple for feeding the record strip, one member of which is 120 connected and the other disconnected from the operating mechanism, and means actuated by the additional device connecting the 125

disconnected member with the operating mechanism when the total is recorded.

17. In a machine of the class described, the combination with a set of type carriers

5 for recording items upon a record strip, of a second set of type carriers for recording upon the record strip the total of said items, the latter set of type carriers being in advance of the item type carriers, and 10 means for feeding the record strip when the total is recorded so as to bring the last recorded item in its proper place above the total.

18. In a machine of the class described, 15 the combination with separate sets of type carriers for recording upon a record strip items and the total thereof, one set of type carriers being in advance of the other, a couple for feeding the strip, and means for 20 moving one member of the couple to feed the strip when the items are recorded and for moving the other member of the couple when the total is recorded so as to bring 25 the last item recorded in its proper place above the total.

19. In a machine of the class described, the combination with a plurality of counters, of an actuating device therefor, a series 30 of keys for adjusting said device differentially in opposite directions, and means for readjusting said device to its normal central position.

20. In a machine of the class described, 35 the combination with a plurality of counters, of an actuating device therefor, a series of keys for adjusting said device differentially in opposite directions to establish co-operative relation with the counters, means for operating said device after such relation is established and mechanism for re-adjusting said device to its normal central 40

position after it has actuated the counter with which said device has been in coöperative relation.

21. In a machine of the class described, 45 the combination with a plurality of counters, of a plurality of keys corresponding in number to the counters, a differentially movable slide actuated by the keys, an actuator for the counters connected to the slide and 50 movable therewith so as to be brought into coöperative relation with any one of the counters, means for operating the actuator after it has been brought into coöperative relation with one of the counters, and mech- 55 anism for readjusting the slide and actuator after the latter has actuated the counter with which it has been in coöperative relation.

22. In a machine of the class described, 60 the combination with a plurality of counters, of a plurality of keys corresponding in number to the counters, a slide adjusted differentially in opposite direction by said 65 keys, an actuator for the counters connected to the slide and movable therewith so as to be brought into coöperative relation with any one of the counters, means for operating the actuator independently of the slide after said actuator has been brought 70 into coöperative relation with one of the counters, and mechanism for readjusting the slide and actuator after the latter has actuated the counter with which it has been in coöperative relation. 75

In testimony whereof I affix my signature in the presence of two witnesses.

HAAKON A. MARTIN.
